HEAD LAMP FOR VEHICLES

Graham Trippe, Chicago, Ill.

Application November 11, 1936, Serial No. 110,324

6 Claims. (Cl. 240—41.5)

My invention relates to head lamps for vehicles.

Among the objects of my invention are to provide a construction whereby the reflectors of the lamp are resiliently positioned so that they are full floating for both horizontal and vertical movement, thereby absorbing shock and greatly lengthening the life of the lamp bulb; to create a structure adapted to seal the interior of the head lamp against moisture, dust, dirt and tarnish, and which when once inserted will not be subject to rattling or accidental removal by vibration or shock; to supply a construction for the adjustment and positioning of the housing in any desired position; to provide an adjustable connection whereby my head lamp may be attached to a vehicle in any desired position; to supply such a connection that will have a construction that my head lamp will be theft proof, and such other objects, advantages and capabilities as will later more fully appear and which are inherently possessed by my invention.

While I have shown in the accompanying drawing a preferred embodiment of my invention, yet I wish it understood that the same is susceptible of modification and change without departing from the spirit of my invention.

Fig. 1 is a side sectional view of my head lamp; Fig. 2 is a front view of the same; Figs. 3 and 4 are detail views of my peculiarly shaped and formed wrench; Fig. 5 is a detail view of the preferred form of my resilient member; and Fig. 6 is a detail view of the adjusting means for my lamp.

Referring more particularly to the embodiment selected to illustrate my invention, it comprises a head lamp 10 having a housing 11, a lens 12, an electric light bulb 13 connected to an electrical source of supply and a reflector 14. A plurality of resilient members 15 are attached by rivets 16 or any other suitable means to the housing 11 and said resilient members are spaced from each other so that their ends 17 contact the back of the reflector 14 at various points, said ends of the resilient members thus acting as a cradle for the reflector. I have found in practice that three resilient members spaced substantially equi-distant form sufficient contact on the back of the reflector, but the exact number of resilient members may be varied without departing from the spirit of my invention. My reflector so positioned is thus full floating and is adapted to move either horizontally or vertically or both simultaneously. Upon the vehicle to which my head lamp is attached hitting a bump or a hole to cause vertical movement, my reflector also moves vertically to absorb the shock and thus greatly increases the life of the electric light bulb.

Since the ends 17 of the resilient members are sharpened they are useful in positioning the re-

flector. The sharpened ends tend to dig into the back of the reflector and thus permanently hold the reflector from twisting or turning after its assembly in place.

After my reflector 14 has been positioned, the bulb 13 connected, the lens 12 is put in place with its inner peripheral edges resting against felt gasket 18 attached to the outer flanged edge 49 of the reflector 14. A ring 19 preferably made in one piece has a V-shaped opening 20 with the wider part of the V on the inner edge and the narrower part on the outer edge. Said ring 19 has a slight outward tapering flange 21 continuing around its outer edge, which flange seats inside the outer edge of the housing which is slightly curved to receive said flange. The ring 19 holds in its substantially hollow grooved interior a gasket 22 of rubber or the like, which is held therein by adhesive or other suitable means. The lens 12 is held between this gasket 22 on the outside and gasket 18 on the inside. Once positioned during assembly, the ring 19 is contracted together with the V-shaped opening 20 adjacent the top of the assembly so that cap 23 may be placed over said ring 19 covering said V-shaped opening 20. Said cap 23 has a pair of rounded grooves 44 to receive the opposite ends of the ring 19, said grooves 44 being separated by a wedge 45 tapering outwardly toward the bottom. Said cap continues backwardly following the contour of the housing 11, and is removably positioned to said housing by a hand screw 24 or the like. Once the cap 23 is placed over the ring 19 the ring may expand so as to insure a tight fit against the gasket 22 and the housing 11, and seal the inside of my lamp 10 against moisture, dirt, dust and tarnish.

Adjacent the bottom of my housing 11 a flange socket 25 is fixed by rivets or other suitable means. Said flange 25 has at its forward portion an upwardly curved lip 26 to receive the central lower portion of the lens retaining ring 19. This lip 26 acts as a guide and holding member for the ring 19 during the operation of assembling when the ring is being contracted and the cap 23 is being placed thereon. Later the lip acts as a secondary support for the ring 19. Said flange socket 25 has substantially at its center a concaved portion 27 having an aperture 28 to receive a bolt 30 of ball washer 29. Said ball washer is of a smaller or equal radius than the radius of the concaved portion 27, and its edges are adapted when so positioned to contact the concaved portion. The ball washer 29 may be adjusted by turning of bolt 30 so that the edges 55 of said washer dig into the concaved portion 27 of flange socket 25 so as to securely hold the lamp 10 in any desired position to which it has been placed by the user. This construction permits easy and exact positioning of my lamp 60

without the creeping that has heretofore been present when adjustment was being made. My construction also insures a permanent positioning once the lamp has been adjusted into place.

5. My supporting arm 31 has an upper curved portion 32 adapted to fit under the concaved portion 27 of the flange socket 25. The bolt 30 passes through the upper concaved portion 32 of the supporting arm 31, and the said concaved portion extends downwardly on either side of nut 47 of bolt 30 forming a recess 51 so that said nut may only be reached and turned by head 46 of my wrench 82 having the peculiar shape necessary to enable it to pass into said recess 51, thus making said adjustment theft proof. The supporting arm continues with a downwardly and outwardly curved shank 33 to end in a serrated bottom 34. The shank 33 has a hollowed out portion 35 towards its lower end so 20 that the head 36 of the bolt 31 cannot be reached and turned except by head 48 of wrench 82 peculiarly shaped to reach into said hollowed out portion 35 of the shank 33. This construction again makes the same theft proof as it cannot be tampered with by the usual run of wrenches, but requires a peculiar tool created for the particular job. Said bolt 37 secures said supporting arm 31 to a standard 38, there being teeth 39 on the standard adapted to engage the serrated bottom 34. The standard 38 is attached to the bumper or other suitable supporting member 40 of a vehicle by means of a clamping plate 43 held by a pair of spaced bolts 41. Said bolts are positioned in recesses in said plate 43 and 35 are surrounded on three sides of the wall of the plate so that they are accessible only by head 48 of my peculiarly shaped wrench 82, adapted to enter into said recess for turning said bolts. This is the third theft proof feature of my lamp.

40 Inasmuch as the supporting arm is movable in a horizontal plane in any direction and the lamp housing in any direction horizontal or vertical by swinging the supporting arm in any desired direction, the lamp itself may be placed wherever desired on the vehicle to protect it from accident and yet to give most efficient service. A set screw 42 cuts through the enamel of the bumper 40 to permit proper electrical contact and to obtain a maximum flow of electricity.

45 Having thus described my invention, I claim:

1. In combination with a head lamp for vehicles having a housing, a source of light, a reflector having a gasket around its outer edge, and a lens, a construction comprising a lens retaining ring having a V-shaped opening and a grooved portion holding a gasket, said lens being held between said gaskets, the V-shaped opening of said ring positioned substantially adjacent the top portion of said housing, and a cap removably fixed to the top portion of said housing placed over said V-shaped opening for holding the ring in place and permitting it to expand to form a seal against the gaskets and the housing.

55 2. In combination with a head lamp for vehicles having a housing, a source of light, a reflector having a gasket around its outer edge, and a lens, a construction comprising a lens retaining ring having a V-shaped opening and a grooved portion holding a gasket, said lens being held between said gaskets, the V-shaped opening of said ring positioned substantially adjacent the top portion of said housing, a cap removably fixed to the top portion of said housing placed over said V-shaped opening for holding the ring in place and permitting it to expand to form a seal against the gaskets and the housing,

60 and a flange attached to said housing adjacent the bottom portion thereof and having a lip adapted to hold and position the bottom of said ring so that said cap may be positioned over the top of said ring.

65 3. A head lamp for vehicles comprising a housing, a source of light, a reflector having a gasket around its outer edge, a lens, a lens retaining ring having a V-shaped opening and a groove holding a gasket, said lens being held between said gaskets, a cap attached to said housing for closing over the V-shaped opening of said ring and for holding said ring against said housing, and a flange attached to said housing having a lip adapted to hold and position one part of said ring so that said cap may be positioned over another part of said ring.

70 4. A head lamp for vehicles comprising a housing, a source of light, a reflector having a gasket around its outer edge, a lens, a lens retaining ring having a V-shaped opening and a groove holding a gasket, said lens being held between said gaskets, a cap attached to said housing adjacent the top portion thereof for closing over the V-shaped opening of said ring and for holding said ring against said housing, and a flange attached to said housing adjacent the bottom portion thereof and having a lip adapted to hold and position the bottom of said ring so that said cap may be positioned over the top of said ring.

5. In a head lamp for a vehicle, a housing, a reflector, an electric light bulb connected through said reflector to an electrical source of supply, a trio of resilient members, each of said resilient members having a plurality of bends, a central portion and a pair of spaced sharp ends, each of said resilient members attached at its central portion to said housing, said resilient members spaced substantially equidistant to form a cradle, said reflector floatingly supported on said cradle so as to provide both vertical and horizontal movement for absorbing shock passed to the vehicle and giving longer life to the electric light bulb, said sharp ends of said resilient members digging into the back of said reflector so as to position said reflector and hold it from turning and twisting out of position.

6. In combination with a head lamp for vehicles having a housing, a source of light, a reflector having a gasket around its outer edge, and a lens, a construction comprising a lens retaining ring having a V-shaped opening and a grooved portion holding a gasket, said lens being held between said gaskets, the V-shaped opening of said ring positioned substantially adjacent the top portion of said housing, a cap removably fixed to the top portion of said housing placed over said V-shaped opening for holding the ring in place and permitting it to expand to form a seal against the gaskets and the housing,

55 and a flange attached to said housing adjacent the bottom portion thereof and having a lip adapted to hold and position the bottom of said ring so that said cap may be positioned over the top of said ring.

GRAHAM TRIPPE.
